UNITED STATES PATENT OFFICE.

JOHN LEWISOHN, OF NEW YORK, N. Y.

METHOD OF COLORED PHOTOGRAPHIC REPRODUCTION.

1,126,495.

Specification of Letters Patent.

Patented Jan. 26, 1915.

No Drawing.

Application filed April 3, 1914. Serial No. 329,254.

To all whom it may concern:

Be it known that I, JOHN LEWISOHN, a citizen of the United States, and a resident of the city of New York, borough of Manhattan, in the county and State of New York, have invented a new and Improved Method of Colored Photographic Reproduction, of which the following is a full, clear, and exact description.

10 This invention relates to a method in which use is made of the blue color of a blue print to superpose a series of different colors to produce a print in substantially natural colors.

15 This invention, while varying from my Patent No. 1,071,559, granted August 26, 1913, utilizes fundamentally the same means.

The method consists in obtaining three negatives of an object to be reproduced on 20 suitable orthochromatic silver emulsion photographic plates with the aid of three respective color screens by the well known three-color photographic process, so that one of the three negatives will produce a positive print with the yellow color value; another, with the red color value; and the third, with a blue color value. The blue print is made first from the yellow color value negative. The entire blue part of this 25 blue print is washed with a yellow wash, such as aurantia, which is then dried and afterward immersed in a weak solution of silver nitrate sufficiently strong to dissolve the blue and leave the yellow image of the 30 yellow color value negative. The so formed print is then washed, to eliminate the silver nitrate and dried. The side of the print bearing the image is then coated with a blue-print sensitizing medium. The sensitizing 35 of the print may be done to advantage before the print is quite dry, to get an even coating. The resensitized print is impressed with an image through the red color value negative, which negative is adjusted on the 40 print so that the image formed by the red color value negative registers with the image under the coating formed by the yellow color value. The blue print so formed is washed with a red color wash, such as red 45 eosin and then dried and treated with a bath of silver nitrate, strong enough to dissolve the blue, leaving the red image on the yellow image previously formed. After washing and drying the so-formed print, the side 50 having the images is recoated with a blue-print sensitizing medium, the same as pre-

viously stated, dried and exposed to produce an image through the negative having a blue color value, which image will properly register with the images formed by the previous negatives. The print so formed will have the blue color, the red color and the yellow color placed successively in the order described; and in combination will produce a picture of substantially natural color, i. e., 65 the image on the print of the object will be substantially in its natural colors.

It is self-evident that the process can be used with only two, or with more than three colors if desired. The principle of the process consists in forming a series of superposing blue images, of which the preceding blue color of the image has been substituted by another color before the succeeding blue image has been formed.

Having thus described my invention, I claim as new and desire to secure by Letters Patent:

1. A method for producing on blue prints a plurality of color effects from different color value negatives, which consists in making a blue print from a negative containing a yellow color value, then treating the blue of the image with a yellow wash and a blue dissolving substance, thus forming a yellow image, then coating the image so formed with a blue-print sensitizer and forming a second blue print from a negative containing red color values, then washing said so-formed second print with a red color wash and a blue-dissolving substance, leaving a red image over the yellow image, then coating said red image with a blue-print sensitizer and forming a blue image thereon from a negative having the blue color values. 95

2. A method for producing on blue prints a plurality of color effects from different color value negatives which consists in forming a blue image, substituting for the blue of the image the color of the same value as the negative with which the blue image has been formed, coating the so-formed image with a blue-print sensitizer, making another blue image, substituting for the blue of the image the color of same value as the negative with which the second blue image has been formed, coating the second image with a blue-print sensitizer and making the final image with a negative having the blue color values. 105

3. A method for producing prints having a plurality of color effects, which consists in

- forming a blue print, substituting for the blue of the image a different color, coating the so-formed image with a blue-print sensitizer, making another blue print, substituting for the blue of the image a color different from the blue and first different color used, coating the so-formed image with a blue-print sensitizer and forming a blue image thereon.
- 10 4. A method for producing prints having a plurality of color effects, which consists in forming a blue print, substituting for the blue of the image a yellow color, coating the

so-formed yellow image with a blue-print sensitizer, forming a second blue print, substituting for the blue of the second image a red color, coating the so-formed red image with a blue print sensitizer and forming a blue image.

In witness whereof I have signed my name to this specification in the presence of two subscribing witnesses.

JOHN LEWISOHN.
